UNITED STATES PATENT OFFICE.

WILLIAM JAMES HOULIHAN, OF PRAHRAN, MELBOURNE, VICTORIA, AUSTRALIA.

DEVICE FOR CLEANSING AND POLISHING THE SURFACES OF FLOORS, WALLS,
WINDOWS, AND THE LIKE.

1,399,427.

Specification of Letters Patent.

Patented Dec. 6, 1921.

Application filed August 10, 1918. Serial No. 249,357.

(GRANTED UNDER THE PROVISIONS OF THE ACT OF MARCH 3, 1921, 41 STAT. L., 1313.)

To all whom it may concern:

Be it known that I, WILLIAM JAMES HOULIHAN, a subject of the King of Great Britain and Ireland, and a resident of the 5 city of Prahran, a suburb of the city of Melbourne, in the county of Bourke, State of Victoria, Commonwealth of Australia, (whose post-office address is 117 Albert street, Windsor, in the said city of Prahran,) 10 have invented certain new and useful Improvements Connected with Devices for Cleansing and Polishing the Surfaces of Floors, Walls, Windows, and the like, of which the following is a specification.

15 This invention relates to means for washing, drying, oiling or polishing floors, floor-coverings such as carpets, linoleum, oil-cloth, and the like, walls, windows, picture glasses and for other such domestic purposes.

The object of the invention is to dispense with the use of the mops and the like at present employed for cleansing and polishing surfaces of the character mentioned and 25 to provide an improved appliance whereby such operations may be performed with a minimum of labor and fatigue. The invention obviates the arduous task of scrubbing or polishing by hand but it has been designed 30 to give as far as possible the efficient effect of such hand labor.

The invention may be used with water for washing floors or other surfaces or it may be used for polishing with oil and such 35 like compositions or simply as a duster.

According to the invention a cleaning fabric is used which may consist of one or more plies of cloth or other suitable material. This fabric is attached to a flat or 40 substantially flat frame in such a manner that it may be quickly attached or removed for cleansing or drying or if desired replaced by another fabric.

The frame has attached to it the lower end 45 of a handle. This is preferably pivoted to the frame or to attachments carried thereby and means are provided for fixing the handle in an angular position most convenient for use.

Referring to the drawings which form 50 part of this specification:

Figure 1 is a plan of a fabric.
Fig. 2 is an end elevation of Fig. 1.
Fig. 3 is a plan of a frame.
Fig. 4 is a view of Fig. 1 looking in the 55 direction of the arrow.

Fig. 5 is a view of Fig. 3 looking in the direction of the arrow.

Fig. 6 is an enlarged sectional view of an eyelet ring and reinforcement in the fabric. 60

Fig. 7 is a plan of a superstructure mounted on a frame. The handle is removed.

Fig. 8 is a side elevation of the superstructure seen in Fig. 7. 65

Fig. 9 is a side sectional elevation.

Fig. 10 is a side elevation of the frame and super-structure with the fabric attached.

Fig. 11 is a sectional elevation of a socket having a locking screw which passes through 70 the handle and into a boss on the superstructure.

Fig. 12 is a side view of a socket having a limit stop extension.

Fig. 13 is a front view of Fig. 12. 75

Fig. 14 is a view on a reduced scale of the invention complete.

On reference to the drawings it will be seen that 2 is a fabric of any suitable material or combination of materials. It is preferably folded back upon itself as seen in Fig. 2. Near each corner of the said fabric are holes 3. At each end of the fabric are situated reinforcing folds 4 of leather, metal or the like also having holes corresponding with the holes in the fabric. Through the holes in the fabric and the holes in the reinforcing folds are placed eyelet rings 5. 80

With the foregoing is used a frame 7. 90 This may be of wood or any other suitable material.

Above the frame 7 is placed a superstructure 9. This has diagonally disposed pin supporting arms 11, from which upstand 95 retaining pins 15. The arms 11 extend from the four corners of the superstructure and through them and also through the body

of the said superstructure are screw holes to pass screws 12 for securing the said superstructure to the frame.

Upstanding from the superstructure is an 5 inclined boss 10 in which is a threaded hole 17.

Upstanding from the said superstructure are also vertical walls 13 having central enlargements 14. Through each of the enlargements is a pin hole accommodating a lateral pivot pin 16. Pivoted to the pivot pin 16 is a socket 18 having an extension 20 through which is a pivot pin hole 19 to accommodate the pivot pin 16.

15 The interior of the socket 18 may be plain or threaded. Into the socket is placed the lower end of the handle 21. This handle may be locked within the socket by being threaded therein or it may be secured there- 20 in by a locking pin 22 (Fig. 12). Or a hole may be drilled through the walls of the socket and through the handle and the hole threaded. Through said threaded hole is then passed a locking screw 23 having a 25 turning head 24, the inner end of this screw being adapted to engage the threaded hole in the boss 10.

Protruding from the socket may be a limit stop extension 25.

30 To attach the fabric the eyelet rings at one end thereof are passed over the retaining pins 15 at one end of the frame. The fabric is then passed beneath the frame and the eyelets at the other end are passed over 35 the other two pins as seen in Figs. 10 and 17.

If the device is to be used for washing a floor or other surface the fabric is immersed in a bucket or other utensil containing wa- 40 ter and then applied to the surface to be treated. On the handle being moved rapidly to and from the operator the surface is quickly cleansed in a highly effective manner the appliances being immersed in the water as frequently as may be desired.

45 When it is desired to dry the surface, the fabric may be quickly removed and wrung out or replaced by a clean or dry cloth.

The device may be used in substantially the same manner for polishing surfaces with 50 oil or other compounds in which case a special fabric may be used for the oil or polishing compound and a separate fabric for polishing purposes. It will be obvious also that the invention may be used for dusting 55 the surfaces of pictures, walls or the like in which case the fabric may be used in a dry state and may be quickly removed and beaten or otherwise treated to remove sur- plus dust as often as required.

60 The boss 10 and the extension 25 on the socket provide limit stops which maintain the handle in correct angular position, the screw 23 when used performs the dual function of retaining the handle in a fixed posi-

tion when it may be necessary and assisting 65 to secure it in the socket 18.

When the limit stop extension 25 is used the boss 10 may be dispensed with, the lower surface of the extension being adapted to engage the face of the superstructure or the 70 frame.

It will be comprehended that the frame 75 may be of other material and construction than that shown which is merely a preferred form. For instance, a frame of metal 75 or of wire or other mesh may in some cases be found preferable. Furthermore various modifications or alterations may be made in the form of the superstructure 9 which instead of being a casting as shown may be 80 cut from sheet metal, suitable lugs being upturned from the metal to provide bearings for the pivot pin 16. Other modifications of a minor character may obviously be made without departing from the nature, 85 spirit and scope of the invention as defined by the appended claims.

Having now described my invention, what I claim as new and desire to secure by Letters Patent is: —

90

1. A device for cleansing and polishing floors and other surfaces, comprising a substantially flat frame, a superstructure attached to one side of said frame, a socket pivoted to said superstructure, a boss up- 95 standing from the superstructure and adapted to engage said socket to support the handle in correct angular position relative to the frame, and a locking screw passing through the socket and the handle and into the boss.

2. A device for cleansing and polishing floors and other surfaces comprising a substantially flat frame, a superstructure attached to one side of said frame, vertical 105 walls to said superstructure, a lateral pivot pin extending between said vertical walls, a handle attached to said lateral pivot pin, a boss upstanding from one end of the superstructure, and a locking screw passing 110 through the handle and engaging said boss.

3. A device for cleaning and polishing floors and the like, comprising a frame, a superstructure attached to one side of the frame and having a pair of longitudinal 115 side walls, an internally threaded boss formed upon one end of the superstructure and arranged between the side walls, a trans-verse pivot pin connecting the side walls and arranged near their centers, a handle on the 120 pivot pin, a boss, a screw passing through said handle and into said boss to lock the handle thereto, and a cleaning element carried by the frame.

4. A device for cleaning and polishing 125 floors and the like, comprising a frame, a superstructure attached to one side of the frame and having a pair of longitudinal side

walls, an internally threaded boss formed upon one end of the superstructure and arranged between the side walls, a transverse pivot pin connecting the side walls and arranged near their centers, a socket mounted on the pivot pin, a handle having one end extending into the socket, a screw passing through the handle and into the boss to lock the socket thereto, and a cleaning element carried by the frame. 10

In testimony whereof I affix my signature.

WM. JAMES HOULIHAN.

Witness:

CECIL W. McPLASTEAD.
